(57) **CLAIM**

The ornamental design for a bucket, as shown and described.

DESCRIPTION

FIG. 1 is a perspective view of an embodiment of the bucket of the claimed design;

FIG. 2 is a front elevational view of the bucket of FIG. 1;

FIG. 3 is a rear elevational view of the bucket of FIG. 1;

FIG. 4 is a right side elevational view of the bucket of FIG. 1;

FIG. 5 is a left side elevational view of the bucket of FIG. 1;

FIG. 6 is a top plan view of the bucket of FIG. 1; and,

FIG. 7 is a bottom plan view of the bucket of FIG. 1.

The features shown in broken lines are environment only and not part of the claimed design.

1 Claim, 7 Drawing Sheets
